(57) **CLAIM**

The ornamental design for an airplane tire fin, as shown and described.

DESCRIPTION

FIG. 1 is a perspective view of an airplane tire fin, shown attached to the rim of an airplane tire;

FIG. 2 is a perspective view of the fin showing my new design;

FIG. 3 is the front view thereof;

FIG. 4 is the back view thereof;

FIG. 5 is the left side view thereof;

FIG. 6 is a right side view thereof;

FIG. 7 is a top view thereof; and,

FIG. 8 is a bottom view thereof.

The broken lines in the drawings depict environmental structure, which forms no part of the claimed design.
